G. F. BORN ET AL

AUTOMATIC RAILWAY SIGNAL

Filed Feb. 14, 1925

Patented Nov. 3, 1925.

1,559,933

UNITED STATES PATENT OFFICE.

GABRIEL F. BORN AND RUSSELL D. BORN, OF NEW PHILADELPHIA, OHIO.

AUTOMATIC RAILWAY SIGNAL.

Application filed February 14, 1925. Serial No. 9,250.

To all whom it may concern:

Be it known that we, GABRIEL F. BORN and RUSSELL D. BORN, citizens of the United States, residing at New Philadelphia, in the county of Tuscarawas, State of Ohio, have invented certain new and useful Improvements in Automatic Railway Signals; and we do hereby declare the following to be a full, clear, and exact description 10 of the invention, such as will enable others skilled in the art to which it appertains to make and use the same.

This invention relates to new and useful improvements in railway devices, and particularly to signaling devices therefor.

One object of the invention is to provide a novel construction of signal, and train operated means for actuating the signal.

Another object is to provide a device 20 which is especially adapted for use at railway crossings, and which produces an audible as well as a visual signal, at the approach of a train to the crossing.

Other objects and advantages will be apparent from the following description when taken in connection with the accompanying drawing.

In the drawing:

Figure 1 is a top plan view of the invention in use.

Figure 2 is a side elevation of the device, showing the relation and connection of the parts.

Figure 3 is a vertical sectional view on the line 3—3 of Figure 2.

Figure 4 is a side elevation of the track trip.

Referring particularly to the accompanying drawing, 10 represents a portion of a railway, and 11 the railway crossing. Mounted on one of the ties 12, of the railway, and at a suitable distance away from the crossing 11, is a bearing bracket 13. Movably supported on this bracket is a rock shaft 14, having a curved arm 15 on one end thereof, said arm being normally held at the approximate level of the tread of the adjacent rail, to be engaged and depressed by the flanges of the wheels of a passing train.

Mounted on the outer ends of the ties, adjacent the bracket 13, and extending to a point adjacent the crossing 11, is a pipe, or other hollow conduit 16, through which extends a cord, wire, or chain 17. On the other end of the rock shaft 14 there is mounted a radial arm 18, and connected

to the outer end of this arm is the adjacent end of the said element 17.

Mounted adjacent the railway crossing is a vertical frame 19, which includes the cross bars 20, 21, and 22, and the uprights 23. Mounted on one of these uprights are the grooved wheels or pulleys 24. Pivotedly supported in an upright position, on the intermediate cross bar 21, is a pendulum 25, the lower end of which has the spaced disks 26, each of which is provided with an opening 27 in which is secured a piece of colored glass 28. On the lower cross bar 22 there is mounted a lantern 29, which is hidden when the disks are in normal position, but which is arranged to be seen through the glass 28, when the pendulum is rocked to dispose the openings 27 opposite said lantern. Secured to and depending from the upper bar 20 is a bell 30, and within this bell is disposed the knobbed upper end 31, of the pendulum 25, and which knobbed end is adapted to strike the bell, upon the pendulum being rocked. Mounted on the upper bar 20 is an electric lamp 32, a wire extending therefrom to a stationary contact member 33, mounted on the bar 21, adjacent the pendulum, as shown at 34, while a wire 35 extends from the lamp to a source of electric current, not shown. Secured on the pendulum 25, in position to engage with the contact member 33, upon rocking of said pendulum, is a contact member 36, from which extends a wire 37, leading to the source of current. A coil spring 38 is connected, at one end, to the pendulum, below the pivot thereof, and at its other end to one of the uprights 23, for the purpose of maintaining the pendulum in normal upright position, and the openings 27 out of line with the lantern.

On one of the ties, adjacent the crossing, and the adjacent end of the conduit 16, is a grooved wheel or pulley 39. The end portion of the flexible element 17, remote from the trip arm 15, is passed around the pulley 39, and the pulleys 24, and is secured to the pendulum, above the pivot thereof.

It will thus be seen that, upon the approach of a train, to the crossing 11, the wheels of the locomotive, and the succeeding cars, will pass over the trip arm, depressing same. This movement of the arm 15 causes the rocking of the shaft 14, which exerts pull on the flexible element 17, with

the result that the pendulum is swung on its pivot to strike the bell, expose the lantern through the openings 27, and close the circuit through the contacts 33 and 36, to light the lamp 32. Thus persons approaching the railway, and in the event that a train is approaching the crossing, will be quickly apprised of the fact by the ringing of the bell, and the showing of the lantern, as well as the electric light. In the event that no electric current is available, the lantern, only, is used, thus providing for audible, as well as visual signals to give warning of the approach of a train.

15 It will also be noted that the coil spring 38 restores the trip arm 15 to normal position, as well as the pendulum.

What is claimed is:

1. A railway signaling device including a bell having a striker, a normally lighted lamp, means on the striker normally concealing the lamp, means carried by the concealing means for exposing the lamp, and means operable by a train for actuating the striker into contact with the bell whereby said concealing means will be moved to expose the lamp.

2. A railway signaling device including

a bell having a striker provided with an enlarged end, said end having an opening 30 adjacent one edge thereof, a light source normally hidden by the unapertured portion of said end, and a train operated means for moving the striker into contact with the bell and simultaneously causing the said 35 enlarged end thereof to be moved to dispose the opening opposite said light source.

3. A railway signaling device including a bell, a striker pivotally supported and engaging bell, a light source, a semaphore on the 40 striker and having an opening normally out of line with the light source when the striker is at rest, a track carried trip member operatively connected with the striker for movement thereof upon actuation of the arm by 45 the wheels of a train, an electric circuit, a lamp and the striker included in the circuit, whereby upon movement of the arm by a train the striker will engage the bell and simultaneously close the circuit through the 50 lamp, and expose the light source through said opening.

In testimony whereof we affix our signatures:

GABRIEL F. BORN.
RUSSELL D. BORN.
